UNITED STATES PATENT OFFICE.

VIOLA C. BROD, OF SANDUSKY, OHIO.

NAIL-POLISHER.

1,389,621.

Specification of Letters Patent. Patented Sept. 6, 1921.

Application filed April 17, 1919. Serial No. 290,897.

To all whom it may concern:

Be it known that I, VIOLA C. BROD, a citizen of United States, residing at 306 W. Water street, Sandusky, in the county of Erie and State of Ohio, have invented a new and original and useful Nail-Polisher, of which the following is a specification.

The present invention, relating, as indicated, to a nail polishing device, is particularly directed to the provision of an improved type of nail polisher or buffer which shall be simple to manufacture and very much more convenient in use than the straight buffers which are now generally used. To the accomplishment of the foregoing and related ends, said invention, then, consists of the means hereinafter fully described and particularly pointed out in the claims.

20 The annexed drawing and the following description set forth in detail certain mechanism embodying the invention, such disclosed means constituting, however, but one of various mechanical forms in which the 25 principle of the invention may be used.

In said annexed drawing:—

Figure 1 is a side elevation of the cylindrical inclosing case of my device; Fig. 2 is a side elevation of the form to be inserted 30 within the case for carrying the polishing material; Fig. 3 is a side elevation of the cap or cover for the case of Fig. 1; Fig. 4 is a side elevation of the complete device; Fig. 5 is a longitudinal central section 35 through the form shown in Fig. 2, but showing the strip of polishing material in place thereon; and Fig. 6 is a transverse section on the line 6—6 in Fig. 4.

In Fig. 4 there is shown the complete device as assembled, consisting of an open-ended cylindrical case or container 1, provided with a removable cap 2. The case 1 is provided with knurling 3 for providing a series of slightly raised projections on the 45 inside of the case to assist in maintaining the polishing device proper in place.

The polishing device proper consists of a tubular member 4 provided with slightly flanged ends 5, and covered by means of a 50 strip of polishing material 6, such as chamois, which is stretched over the inside walls of the member 4, and is then re-bent around the flanged ends 5. This polishing material is held in place by some readily re-

movable means such as a thread 7 wrapped 55 several times around the re-bent ends of the chamois to hold the latter tightly against the outer edges of the form 4. The strip of polishing material may be either left in the form of a straight strip or two opposite 60 ends may be sewed together to form a complete tube which will fit snugly within the form 4.

The chamois projects sufficiently over the edge or flange 5 on the form 4 to snugly engage against the knurling on the inside of the cylinder 1, there being sufficient friction between the chamois and the walls of the case to ordinarily maintain the buffer in place while in use, although the friction is 70 insufficient to prevent the buffer from being removed when it is desired to replace the chamois.

In use the device is held in one hand, while a person inserts one finger of the other 75 hand into the open end of the buffer with either a longitudinal or oscillatory circular motion, in this way polishing the nail against the surface of the chamois. By pushing the finger longitudinally into the buffer, while 80 at the same time pressing the nail against the chamois, the cuticle about the edges of the nail is forced back very much more effectively than can be done with the relatively straight buffers that are now in use. 85 Furthermore, my polisher can be used without rubbing the flesh at either side of the finger nail, which is one objection to the use of the straight polisher. The present device is extremely small and compact and is very 90 much smaller than the straight buffers which are now generally used.

Other modes of applying the principle of my invention may be employed instead of the one explained, change being made as 95 regards the mechanism herein disclosed, provided the means stated by any of the following claims or the equivalent of such stated means be employed.

I therefore particularly point out and distinctly claim as my invention:—

1. In a device of the character described, the combination of a receptacle provided with an opening, said receptacle having a nail polishing material secured to its inner 105 walls adjacent such opening.

2. In a device of the character described, the combination of an open-ended receptacle

provided with nail polishing material covering its inner walls adjacent the open end thereof.

3. In a device of the character described, 5 the combination of a cylindrical case open at one end, and a tubular member covered with nail polishing material on its inner walls, said member being removably mounted in said case.

4. A nail polisher consisting of an open- 10 ended tubular member provided with nail polishing material upon its inner wall.

5. A nail polisher consisting of an open-ended tubular member and a strip of nail 15 polishing material removably secured thereto, said strip being disposed in said member to cover the inner wall thereof.

VIOLA C. BROD.
